UNITED STATES PATENT OFFICE.

HENRY B. JONES, OF YONKERS, NEW YORK.

JACK.

1,145,315.

Specification of Letters Patent.

Patented July 6, 1915.

Application filed February 20, 1915. Serial No. 9,615.

To all whom it may concern:

Be it known that I, HENRY B. JONES, a citizen of the United States, residing at Yonkers, in the county of Westchester and 5 State of New York, have invented certain new and useful Improvements in Jacks, of which the following is a specification, reference being had to the accompanying drawings.

10 This invention relates to new and useful improvements in lifting jacks and more particularly to an automobile jack, the main object of the present invention being the provision of a hoisting jack which is particularly adapted for raising automobile 15 axles and is so constructed that it can be quickly and readily raised or lowered and securely held when in its raised position.

Another object of the present invention is 20 the provision of a hoisting jack wherein the upper bearing face is adjustable with respect to the main portion of the jack, so that the device can be quickly and readily adjusted to accommodate vehicles of various 25 makes and, at the same time, it will be noted that the device can be used for various other purposes.

With the above and other objects in view, the invention consists in the novel features 30 of construction, combination and arrangement of parts as will be hereinafter referred to and more particularly pointed out in the specification and claims.

In the accompanying drawing forming a 35 part of this application, Figure 1 is a side elevation of my improved jack, parts thereof being broken away and illustrated in cross section. Fig. 2 is a front elevation, the handle of the actuating lever being 40 shown in cross section. Fig. 3 is a transverse sectional view on the line 3—3, Fig. 1. Fig. 4 is a top plan view of the retaining member for the adjustable support; and Fig. 45 5 is a side elevation of the cam-shaped head illustrating a slightly modified form of the invention.

In carrying out my invention, 1 indicates the base member and extending upwardly from the base member, are the spaced standards 50 2 integrally connected at the upper end, as shown at 3 to form a guide through which the casing 4 is movable. The casing 4 is cut away upon opposite sides thereof at its lower end to provide spaced arms 5 and 55 rotatably mounted between these arms, is a roller 6, the purpose of which will be here-

inafter more fully set forth. Movable disposed within the upper end of the casing 4, is an adjustable rack 7, the opposite sides of which are provided with the spaced lugs 8 and the top thereof provided with a supporting plate 9. This rack 7 is movably disposed within the casing 4 and securely held in an adjusted position by means of the key 10 consisting of a body which is bifurcated 65 at one end to form spaced arms 11 adapted to be inserted between the lugs 8 on the rack 7 and bear against the upper edge of the casing 4 to securely retain the rack in an adjusted position. The opposite end of the 70 key 10 is provided with an opening 12 whereby when the key is not in use, it may be readily suspended from the projection 13 formed upon the side of one of the standards 2. It will be noted that the standards 2 are 75 connected at their lower ends by means of the transverse strip 14, the purpose of which will be hereinafter more fully set forth.

Extended transversely between the standards 2, is a shaft 15 and eccentrically mounted thereon is a cam 16, the upper face of which is adapted to contact with a roller 6, whereby upon actuation of the cam 16, the casing 4 will be moved vertically between the standards 2. It will be noted that the 85 inner faces of the standards are provided with vertically disposed grooves within which the sides of the casing are movable, whereby to prevent any lateral movement of the casing, while arranged between the 90 standards. The bearing face of the cam is substantially wider than the body of the cam to provide for a suitable bearing surface. This face extends out upon the lever 18 which is formed integral with one end of 95 the cam so that a person's foot may be readily applied to the upper face of the lever to press the same downwardly in a locked position.

As illustrated in Fig. 1, the cam is in its 100 inoperative position and in order to actuate the same to raise the casing 4, the lever 18 is moved downwardly, the rollers 6 riding over the bearing surface of the cam and raising the casing 4. When the lever 18 reaches the end of its downward stroke, the shoulder 19 will engage with the pivoted latch bar 20 so as to securely hold the cam in its locked position and retain the casing 4 in its raised position. The latch bar 20 is 105 pivotally connected between the upstanding lugs 21, while the outer end thereof is mov-

able within a yoke 22 and normally retained in a raised position by means of the spring member 23 disposed beneath the latch bar. Thus, when it is desired to release the lever 18 so that the weight upon the upper end of the rack 7 will move the cam to its inoperative position, the outer end of the latch bar 20 is pressed downwardly to disengage the same from the shoulder 19. As the lever 18 reaches the end of its downward stroke, the shoulder 24 opposite the shoulder 19 will engage with the transverse strip 14 and prevent further movement of the lever in a downward direction and, when the cam 16 is 15 in an inoperative position as shown in Fig. 1, the lower edge thereof rests upon a supporting hook 25, which is formed integral with one end of the base.

In operating my improved jack, the rack 20 7 is adjusted according to the object to which the device is to be applied. The key 10 is then engaged between the lugs 8 to retain the rack in its desired position. The jack is then placed beneath the object to be raised 25 and the lever 18 moved downwardly toward the base 1, whereby the roller 6 will move over the cam surface of the eccentrically mounted cam 16 and raise the casing 4 between the standards 2. As the lever 18 reaches its 30 downward stroke, the shoulder 19 will engage with the latch bar 20 to retain the jack in its raised position. When it is desired to release the lever 18, the outer end of the latch bar 20 is pressed downwardly against 35 the tension of the spring 23, so as to disengage the same from the shoulder 19, the weight of the object upon the rack 7 turning the cam and lever to an inoperative position.

It will be noted that the body portion of 40 the cam 16 is provided with a hexagonal and octagonal opening which is adapted to be used, should it be desired to use the device as a wrench for removing axle nuts. The cam may be quickly and readily removed 45 from between the standards 2 by withdrawing the shaft or pivot pin 15. Thus, it will be apparent that the device can be quickly and readily removed from between the standards and used for removing axle nuts 50 or the like.

In Fig. 5, I have illustrated a slightly modified form of the invention, wherein the upper face of the cam 16' is provided with a plurality of teeth which are adapted to 55 engage with the gear 6' which is used in

place of the roller 6. From this it will be apparent that either the smooth surface of the cam 16 may be used or the cam may be provided with teeth, as illustrated in Fig. 5 and the roller 6 replaced by the gear 6'.

60

My improved hoisting jack, as herein shown and described, is extremely simple in construction, and can be manufactured and placed upon the market at a comparatively 65 low cost.

65

While I have shown and described the preferred form of my invention, it will be obvious that various changes in the details of construction and in the proportions may be resorted to for successfully carrying my 70 invention into practice, without sacrificing any of the novel features or departing from the scope of the invention, as defined by the appended claims.

70

Having thus described this invention, 75 what I desire to claim as new and secure by Letters Patent, is:—

1. A lifting jack including spaced standards, a casing movable vertically between said standards, a movable element carried by the casing, a cam eccentrically mounted between the standards and movably engaging the movable element for raising and lowering the casing, a lever formed integral with the cam, a shoulder formed at the inner end 85 of the lever, a spring actuated bar adapted for engagement by the shoulder when the lever is in a lowered position, said bar being manually operated to release the lever whereby weight upon the upper end of the 90 casing will return the cam to an inoperative position.

85

2. A lifting jack including spaced standards, a casing movable vertically between the standards, a supporting member vertically adjustable in the casing, vertically spaced, horizontally disposed teeth formed on opposed faces of the supporting member, a substantially U-shaped key for holding the supporting member in a vertically adjusted 100 position with respect to the casing, the arms of said key being engageable between the teeth of the supporting member, and means for vertically adjusting the casing.

95

In testimony whereof I hereunto affix my 105 signature in the presence of two witnesses.

HENRY B. JONES.
